UNITED STATES PATENT OFFICE.

GEORGE B. GRAFTON, OF MCKEESPORT, PENNSYLVANIA, ASSIGNOR TO WESTMORELAND AUTOMATIC MACHINE COMPANY, OF IRWIN, PENNSYLVANIA, A CORPORATION OF PENNSYLVANIA.

SHOE-POLISHING MACHINE.

1,088,563.

Specification of Letters Patent. Patented Feb. 24, 1914.

Application filed July 24, 1911. Serial No. 640,140.

To all whom it may concern:

Be it known that I, GEORGE B. GRAFTON, a resident of McKeesport, in the county of Allegheny and State of Pennsylvania, have 5 invented certain new and useful Improvements in Shoe-Polishing Machines, of which the following is a specification.

This invention relates to the general type of shoe polishing machines, for instance as 10 shown in patent to Frank Magidson, No. 919,903, April 27, 1909, wherein separate brushes are employed for cleaning and polishing the toe or front and the side portions of the shoe.

15 In the development of the present improvements, the toe and side brushes are so connected by suitable gearing that all of said brushes are rotated by a single drive shaft which is movably mounted for the 20 purpose of traveling with the shifting brushes, thus rendering the driving mechanism more simple, direct, and compact than heretofore.

A further purpose is to control the intermittent operation by a timing shaft and parts operated thereby of improved construction and arrangement.

In the accompanying drawings, Figure 1 is a side elevation of the mechanism within 30 the casing or cabinet with the parts in the positions they occupy when at rest preceding the starting of the polishing operation, at such time all of the brushes being at the inward limit of their travel. Fig. 2 is 35 an elevation of the brush mechanism at the outward limit of travel, the brushes being shown in operative relation with a shoe being polished. Fig. 3 is a plan view of the mechanism partly in section, the plane of 40 section through the toe brush mechanism being indicated by line 3—3, of Fig. 2. Fig. 4 is a sectional plan on line 4—4, of Fig. 5. Fig. 5 is a sectional elevation taken on line 45 5—5, of Fig. 4. Fig. 6 is a vertical section taken through the toe brush mechanism on line 6—6, of Fig. 2. Fig. 7 is a detail of one of the side brushes, and Fig. 8 is a similar view of one of the side brushes, together with a diagrammatic illustration of the op-

erating mechanism common thereto and to 50 the toe brushes. Fig. 9 is a detail partly in section of the coin chute and coin-holding and releasing mechanism, and Fig. 10 is a similar view illustrating positions of the parts when the coin or check is released. 55 Fig. 11 is a detail of the air pump operating clutch. Fig. 12 is a detail of the timing shaft and parts coöperating therewith, and Figs. 13 and 14 are sectional elevations taken on lines 13—13 and 14—14, respectively, of 60 Fig. 12. Fig. 15 is a sectional detail of one of the liquid polish atomizers.

Referring to the drawings, the cabinet in which all of the mechanism is inclosed consists of a forwardly extending portion 2 open 65 at the top at 3 for inserting the foot, the rear upright part 4 of the cabinet being higher than the front portion, as shown.

Within the cabinet all of the mechanism is preferably mounted on a base plate 5, with 70 posts or standards 6 rising therefrom and supporting shelf 7 on which an electric motor 8 is mounted. Armature shaft 9 of the motor is geared at 10 to the relatively short shaft 11, and the latter is in turn geared at 12 to the downwardly extending shaft 13 which at its lower end is connected by the worm gearing 14 with transverse shaft 15, the latter being provided at its ends with cranks 16 which effect bodily movement of 80 the brushes relatively to the foot support, as will be presently explained.

Secured to base 5 at the transverse center of the machine is the foot rest 17, and extending along opposite sides thereof are the 85 two upper rods 18, and beneath and parallel with the latter are similar rods 19. The pairs of rods thus located at opposite sides of the foot support form tracks on which slide the frames 20 which carry the side 90 brushes 21, also the liquid polish containers 22, each of the latter having a bottom rib 23 which is removably entered between the top flanges 24 of frame 20, see Figs. 1, 2 and 4. The side brushes 21 are rotatable about vertical axes at the free end of the bracket-like arms 25 which are hinged at 26 to the inner sides of frames 20, springs 27 being pro-

vided on the rods of hinges 26 for holding the brushes normally in close proximity to each other and to the foot rest, as in Figs. 3 and 4, stops 28 and 28' on frame 20 and arm 25, respectively, limiting such movement so that the brushes cannot swing outward or toward each other too far. In order to insure close contact of the brushes with the heel portion of the shoe, the brush-carrying arms or brackets 25 engage the yielding bar or stop 25', Figs. 2, 3 and 4, and are forced together and around the heel, overcoming any tendency the brush bristles might have to prevent such close contact. Also slidable on the upper track rods 18 is the transverse toe brush support or carriage 29, which is depressed or yoke-shaped between the tracks, see Fig. 5, to permit the toe brushes to operate. Journaled in carriage 29 is the transverse shaft 30, and rotatably mounted on this shaft is frame 31 which carries the oppositely disposed toe brushes 32 and 33, the former serving to spread liquid polish and partially 25 develop the shine, and brush 33 acting as a buffer to fully complete the same. These toe brushes, or more strictly brush 32 and buffer 33, are of the general construction and arrangement shown in Patent No. 919,903 30 above referred to, but the brush actuating or driving mechanism is somewhat differently arranged, as will presently appear.

The mechanism which slides or reciprocates the side brush carrier 20 and the toe brush carrier 29 on the horizontal tracks is the same at each side of the machine, each of these side mechanisms consisting of a lever 35 fulcrumed at 35' to base 5, with the upper extremity of the lever connected by link 36 with frame 20, and the lever beneath its upper end connected by link 37 with frame or carriage 29. Beneath said connections link 38 connects lever 35 with crank arm 16 on shaft 15. It is necessary for the side brushes to travel farther than the toe brushes, and with levers 35 and their several link connections arranged as shown, the brush supports 20 are caused to slide more rapidly on the tracks than the toe brush support 29, with the result that as the side brushes move from the heel to the toe of the shoe they gain appreciable distance on the toe brush, being considerably closer thereto when they reach the limit of such movement, as in Fig. 1, than when such movement is started.

A characteristic of the invention is the simple and compact mechanism provided for rotating the several brushes. All of the movements are communicated from the single upright drive shaft 40 which is flexibly connected to support 29 by the socket-like joint 41, Fig. 6, the movement of shaft 40 being compensated for at its driven end

by yoke-like bearing 42 mounted to oscillate 65 on the armature shaft 9, shaft 40 being slideable through but splined to gear 43 mounted in yoke 42, with said gear meshing with gear 44 on shaft 9, as shown in Fig. 1.

The lower end of shaft 40 is geared at 45 to shaft 30 on support or carriage 29, Fig. 6, and carried by this shaft is gear 46 which meshes with gear 32' of toe brush 32, also with like gear 33' of buffer 33, Figs. 3 and 8, with the result that both of said brushes 32 and 33 are rotated in unison. The mechanism for releasing and reversing said brushes will presently be described. In addition to driving the toe brushes shaft 30 is geared to the short vertical shafts 47 at 80 either side of support or carriage 29, Figs. 6 and 8, and geared to the lower ends of shafts 47 are the tubular portions 48 of the extensible shafts which drive the side brushes, the solid portions 49 of said shafts 85 sliding longitudinally within the tubular portions 48 and having pin-and slot connections 50 therewith, see Figs. 3 and 8. The outer ends of shafts 48-49 are journaled in the outer ends of swinging arms or brackets 90 25 and are geared at 51 with spindles 21' of the side brushes, as in Fig. 8. The extensible or telescoping power transmitting shafts communicate requisite motion to the side brushes from the same mechanism that 95 drives the toe brushes, and at the same time compensate for the variations in travel of the toe and side brushes.

The toe brush carrying frame 31 is prevented from rotating with shaft 30 by one 100 or the other of two latch arms 55 and 56 pivotally supported at the rear side of carriage 29, each latch arm carrying a notched head 57 which slides thereon, being held normally raised by the cushioning spring 57'. 105 The head 57 of latch arm 55 is adapted to engage a lug 58 at one end of frame 31 for holding the latter with toe brush 32 in operative position, while a similar lug 58' at the opposite end of frame 31 is adapted 110 to be engaged by the head of latch arm 56 for so holding the frame as to cause buffer 33 to operate on the shoe. Adapted to turn with each of latch arms 55 and 56 is an arm 115 59, and the upper end of each arm carries a stop screw 60 for limiting the inward movement of the latch arm against the pull of a spring 61. The lower extremity of each arm 59 forms a trip 59', and the backward movement of the support or carriage 29 places these trips in the path of wipers 62 120 mounted on transverse shaft 63, Figs. 1 and 5, the rotation of shaft 63 being so timed as to engage the trips 62 when support 29 is in its rearmost position, Fig. 1, thus tipping or 125 tilting both latch arms and releasing frame 31, whereupon the latter turns through half a revolution or until the lug 58 or 58', as

the case may be, on the other end of the frame engages its notched latch 57, thus again locking frame 31 with one or the other of brushes 32 or 33 held in operative position. The latch heads 57 are beveled as shown so that the lugs on frame 31 will readily deflect and engage the same, at such time springs 57' permitting the latch heads to yield downwardly and thus cushioning what would otherwise be a sudden and possibly damaging jar on frame 31. Also, the springs yieldingly oppose upward tilting or swinging of the active brush when operating on the shoe, Fig. 2, and maintain sufficient pressure to make the operation of the brush effective. The turning of shaft 30 tends to rotate frame 31 when the latter is unlatched, but to insure this movement a spring 64, coiled on shaft 30, bears against a stop on said shaft and on the inner side of the frame, Figs. 3 and 6, thus frictionally connecting the parts.

Shaft 63 is geared at 65 to shaft 15, Figs. 1 and 4, and this shaft 63 in addition to carrying wipers 62 operates to drive the vertical shaft 66 which extends upwardly and is geared to the timing shaft 67 located in the upper portion of the machine at the rear of the motor.

The timing mechanism actuated by shaft 67, *i. e.*, the mechanism for making and breaking the main motor circuit, is shown in detail in Figs. 12, 13, and 14. Secured to shaft 67 is head 68 of insulating material provided on one face with a flat metallic ring 69 which is constantly engaged by the spring contact 70 at terminal B of the main motor circuit A. Spaced from head 68 is the non-rotatable head 71 of insulating material which is cushioned by spring 71' on its support 72, and with the face of head 71 provided with a cam or wedge-shaped metallic ring 73 which is formed with a break or interruption, as indicated at 74. A pin 75 is extended through head 71, and connected to this pin is the other terminal C of the main motor circuit A. A pin 76 carried by head 68 is moved by the latter over the face of ring 73 and the circuit is closed until said pin reaches interruption 74, Fig. 13, when the main motor circuit is broken and the machine is brought to a standstill.

To start the machine, a starting circuit is utilized which operates in conjunction with a coin chute, which I will now describe. The coin chute 77 is adapted to receive a coin or check S of whatever denomination through the drop 77' which may be conveniently arranged in the top of cabinet 4. One terminal b of the starting circuit a is connected to the chute, Figs. 9 and 10, and the other terminal c of said circuit is connected to the vertically swinging latch 78 pivoted to the chute. A V-shaped detent 79 is pivoted in the chute with one arm 80 thereof located

within the chute and the other arm projecting through a slot and into the path of latch 78, but normally disengaged therefrom, the normal position of the detent being as shown in full lines in Fig. 9. When a coin or check S is dropped into the chute and engages the detent, the latter is turned to the dotted line position of Fig. 9, thereby engaging its arm 81 with the insulated latch contact member 78' to which the circuit terminal c is connected, at the same time holding the coin or check lodged in the chute, as in Fig. 9. Thus, the starting circuit a is closed to the coin chute, detent 79 and latch contact 78' and the motor is started, whereupon contact pin 76 is moved from the position indicated in Fig. 13 into engagement with the surface of ring 73 thereby again opening the main circuit. The starting of the machine causes the wiper 82, Fig. 9, on shaft 67 to engage lever 83 when the latter raises latch 78 and permits the detent arm 80 to swing downwardly or backwardly, as in Fig. 10, and releases the coin which latter then drops into the coin box 84, the machine continuing to run until contact pin 76 again reaches interruption 74 when the machine comes to a standstill. As thus arranged, the machine is designed to provide one complete operation for each coin or check inserted, a penny or a one cent piece for instance, so that both shoes are automatically cleaned and polished for two cents. Being primarily a "penny" machine, no special provision is had for guarding against operation with slugs, though it may be operated by any coin or slug that is not too large.

As here embodied, each liquid polish container 22 has a spraying or atomizing nozzle 85 which is connected by flexible tube 86 with an air pipe 87 extending from a pivotally mounted pump 88, the piston of the latter being operated by a crank 89 normally loose on the extremity of shaft 11, Figs. 1, 5 and 11. For operating the crank arm, it is provided with a clutch face which is adapted to be engaged by clutch head 90 slideable on and rotatable with shaft 11, said clutch adapted to be thrown out by lever 91 against the pull of spring 92, Fig. 11. Normally, lever 91 holds the clutch disengaged, but when a projection on the lever registers with depression 93' in a wheel 93 secured to shaft 67, the spring throws the clutch in momentarily and several strokes are imparted to the pump piston which are quite sufficient to provide the necessary spraying action. It will be understood that this operation of the pump is so timed as to spray a shoe during such portion of the travel of the container carrying frames 20 as is necessary to effectively apply the same to the several parts of the shoe.

Each atomizer may be constructed as

shown in Fig. 15, the sprayer head being mounted on the upper end of a tube 94 depending into container 22, with nozzle 95 at the inner extremity of air tube 86 to project air through head 85 in such manner as to induce an upward and outward spray of fluid, as will be understood.

I claim:

1. The combination of a foot rest, a rotatable toe brush, rotatable side brushes, separately movable supports for said brushes, support moving means, a shaft carried by the toe brush support, gearing connecting said shaft with all of the brushes, and a drive shaft movable with the toe brush support and geared to the first mentioned shaft.

2. The combination of a foot rest, rotatable side brushes movable bodily relatively to the foot rest, a rotatable toe brush movable bodily relatively to the foot rest and at a different speed from the bodily movement of the side brushes, a drive shaft, and mechanism operatively connecting the shaft with all of said brushes, said mechanism including longitudinally extensible shafts interposed between the toe and side brushes which compensate for the variations in speed at which said brushes move.

3. The combination of a motor shaft, a horizontal shaft beneath and geared to the motor shaft; a foot rest, rotatable brushes, supports for the brushes movable relatively to the foot rest, means connecting said horizontal shaft with the supports for moving the latter, a brush driving shaft movable with one of said supports, a bearing through which said shaft moves longitudinally, said bearing being mounted to oscillate concentrically with said motor shaft, and gearing connecting the motor shaft and said brush driving shaft.

4. The combination of a foot rest, brushes for operating on different parts of the shoe, a movable support for each brush, a lever connected to the respective supports at different distances from the lever fulcrum whereby the supports are moved at different speeds, and means for actuating the lever.

5. The combination of a foot rest, supports at opposite sides of the rest and movable longitudinally thereof, a movable toe brush support, side and toe brushes carried by the respective supports, a pair of levers with each lever connected to a side brush support and also to the toe brush support, said connections being at different distances from the lever fulcrum whereby the supports are moved at different speeds, and lever actuating means.

6. The combination of a foot rest, a toe brush, a toe brush support slidable toward and from the front of the foot rest, side brushes, supports for the side brushes dis-

tinct from the toe brush support and slidable longitudinally of the foot rest, a pair of levers with each lever connected to the toe brush support and to a side brush support, and lever actuating means.

7. The combination of a foot rest, a brush support, means for moving the support toward and from the foot rest, a brush rotatably mounted on the support, a power shaft, a transmission shaft pivotally and slidably connected to the power shaft and pivotally connected to the brush support, and gearing connecting the transmission shaft and brush.

8. The combination of a foot rest, rotatable side brushes, supports for the side brushes movable longitudinally of the rest, a toe brush, a movable toe brush support distinct from the side brush supports, means for moving the several brush supports, a power transmission shaft movably connected to one of the brush supports, and gearing connecting said shaft with the several brushes.

9. The combination of a foot rest, rotatable side brushes movable bodily longitudinally of the rest, a rotatable toe brush movable bodily toward and from the rest, means for moving the side brushes bodily, means for moving the toe brush bodily and at a different speed from that of the side brushes, a power transmission shaft movable with 95 and geared to the toe brush, and compensating gearing connecting said shaft with the side brushes for rotating the latter irrespective of the difference in bodily movement between the side and toe brushes.

10. The combination of a foot rest, side brushes, side brush supports at opposite sides of the foot rest and slidable longitudinally thereof, a toe brush, a toe brush support slidable relatively to the foot rest, actuating means for the several supports, and brush actuating mechanism.

11. The combination of a foot rest, side and toe brushes, a separate support for each brush with all of the supports slidable longitudinally of the foot rest, support actuating means connected to all of the supports, means for causing the actuating means to move the side brush supports a greater distance than the toe brush support, and brush actuating means.

12. The combination of a foot rest, tracks extending longitudinally of the foot rest, separate side and toe brush supports movable on the tracks, side and toe brushes rotatably mounted, respectively, on the supports, means for moving the supports on the tracks, and brush rotating means.

13. The combination of a foot rest, tracks at opposite sides of the foot rest and extending longitudinally thereof, separate side and toe brush supports movable on the tracks, support actuating means for simultaneously

moving the separate supports, a toe brush holder rotatably mounted on the toe brush support, toe brushes rotatably mounted in the holder, means for rotating said holder, side brushes rotatably mounted on the side brush supports, and means for rotating the side and toe brushes.

In testimony whereof I affix my signature in presence of two witnesses.

GEORGE B. GRAFTON.
